UNITED STATES PATENT OFFICE.

FRANK S. INGOLDSBY, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

RAILWAY-CAR.

SPECIFICATION forming part of Letters Patent No. 767,693, dated August 16, 1904.

Application filed December 10, 1903. Serial No. 184,637. (No model.)

To all whom it may concern:

Be it known that I, FRANK S. INGOLDSBY, a citizen of the United States, residing at St. Louis, in the State of Missouri, have invented 5 a certain new and useful Improvement in Railway-Cars, of which the following is a full, clear, and exact description, reference being had to the accompanying drawings.

The object of my invention is to produce a 10 light and strong railway-car, and while the principles are practically adapted to dump-cars of the type known as "Ingoldsby" dump-cars the invention is not limited thereto.

It has been proposed heretofore to lighten 15 the weight of the central beam of cars by dividing the same at its center and supporting the central ends of the same by a cross-beam secured to the sides, the outer ends of such longitudinal beam extending to and being supported by the bolsters. By this construction 20 a part of the load formerly carried by the longitudinal beam is transferred to the sides, and where the sides are trussed or are of considerable height they may easily carry the 25 extra load thus transferred. I have shown, described, and claimed such construction in my application Serial No. 120,959, filed August 25, 1902.

The construction above described is objectionable in that it unduly weakens the central 30 longitudinal beam.

The object of my invention more particularly is to secure the advantages incident to the construction referred to above without in- 35 curing any of the disadvantages thereof.

Referring to the drawings, Figure 1 represents a side elevation of my central longitudinal beam, the bolsters, cross-beam, and tie-rod being shown in section, the hood inclosing 40 the cross-beam being removed for clearness of illustration, and a portion of said longitudinal beam being broken away to show the filler-block. Fig. 2 represents a transverse section of a car, showing one embodiment of 45 my invention applied to the longitudinal beam. Fig. 3 represents a sectional detail of a wooden longitudinal beam having my invention applied thereto. Figs. 4, 6, 8, 10, and 13 rep-

resent details in elevation of modifications of the strut and tie member shown in Fig. 2. 50 Fig. 5 represents a somewhat diagrammatic plan view of the floor-frame of my car between the bolsters thereof. Figs. 7, 9, and 11 represent sectional details of the tie-rods and beams shown in Figs. 2, 8, and 10, respectively. Fig. 12 represents a sectional detail of a modification of the structure in Fig. 11.

Describing the parts by letters, A represents the central longitudinal beam, said beam, 60 as shown, extending continuously between the bolsters B B. Through or near the neutral axis of the beam A extends the cross beam or member C, a hole being cut through the longitudinal beam at or near the neutral 65 axis, as shown at a'. Adjacent to the lower edge of said longitudinal beam may be hinged the door K, usually employed in the Ingoldsby cars.

The beam A, as shown in Figs. 1, 2, and 5, 70 is made of metal, preferably steel, and in small cars or where a commercial sheet-plate of sufficient length may be obtained said beam will be made of one piece of steel. It may, however, be made of as many pieces as convenient without affecting the spirit of my invention. Interposed between the beam C and the ridge of the longitudinal beam is the filler-block a, said block being of the form shown in Figs. 1, 2, and 5 and being secured, as by 75 riveting, to said beam and member.

The beam C, which is shown as an I-beam, is suitably secured to the longitudinal beam or member, as by means of a flanged plate c, secured to each side of the beam C and riveted 85 to the longitudinal beam, said plate conforming in shape to the intersecting portion of the beams A and C. The ends of said beam C are secured to the car sides, as by flanged plates c' c', riveted to opposite sides of said beam and 90 to the car side. The exposed portions of the beam C are covered by a bent plate or hood H, extending from the longitudinal beam to the sides of the car.

My invention is shown in Fig. 2 as applied 95 to a car having a plate-girder side D, provided

with upper and lower chords d d' , respectively, said side being connected to or supported by the bolsters B.

In order to strengthen the beam C, I employ 5 the strut E and the tie G. The strut is suitably secured to the lower side of the member C and is provided at its lower end with a bifurcation e, adapted to receive the tie, the ends of the tie passing through the car sides (see 10 Figs. 2, 3, 8, 10, and 13) and being provided with threaded ends g, having nuts g' for adjusting the tension of said tie. Suitable bearing-castings for the nuts g' are provided at g'.

Instead of employing a rod as the tie I may 15 substitute therefor a flat plate G', such as is shown in Fig. 4, the ends of said plate being bent up around the ends of the beam C between the same and the car side and being there secured, as by rivets g³, extending 20 through the flanges of the plates c' and the car side D. The end of the plate G' may extend up on the inside of the car side, as shown, and be riveted thereto as additional support for the end of beam C.

25 In Figs. 2 and 7 I have indicated one manner of extending the tie-rod through the side—viz., by cutting a hole through the lower flange and the web of the beam C of sufficient size to enable the tie-rod to pass therethrough. 30 The plates c' are bent to conform to the tie-rod and are sufficiently strong and sufficiently well riveted to the web of the beam C to compensate for the metal thus cut away.

The construction shown in Figs. 8 and 9 35 agrees with that shown in Figs. 2 and 7, except that the cut through the beam C is made closer to the outer lower corner thereof, thereby cutting away less of the metal of the beam than is the case in the construction shown in 40 Figs. 2 and 7.

In Figs. 10 and 11 I have shown a simple 45 and efficient manner of extending the tie-rod through the car side without material injury to the beam C. In this case I simply make a saw-cut in the lower corner of C and spread the parts of the beam apart sufficiently to allow the passage of the rod G.

Fig. 12 represents a construction identical 50 with Fig. 11, save that the beam C' is made of two channel-beams placed back to back instead of being made of an I-beam.

In Fig. 13 the rod G is shown as passing 55 through a hole cut in the lower flange of the beam C and through the flange c² of the plate c' and the side D, passing on one side of and close to the web of the beam C. The other end of the rod will preferably pass on the other side of said web.

As a further modification of the manner of 60 securing the ends of the tie-rod the same may be flattened out and riveted to the web of the member C, as shown in Fig. 6.

My invention has been described thus far as 65 applied to a metallic car, the car having a metallic longitudinal beam. I may, however, employ

the same in connection with a longitudinal wooden member, such as is shown in my Patent No. 720,031, granted February 10, 1903. This longitudinal member A' may be itself composed of several members, as is the case 70 with the construction shown in the patents cited. In such case the hole is cut through or near the neutral axes of the individual members, as shown in Fig. 3, the cross-beam C' extending through said hole. In this case 75 in order to give a sufficient amount of bearing-surface I provide the strut E' with two supporting-arms F, engaging the lower surfaces of the main longitudinal members. The cross-beam C' may be of wood, as indicated 80 in the figure, and may be suitably secured, as by tenoning, into the wooden side sill or chord d'.

Having described my invention, I claim—

1. In a car, the combination of the sides, 85 bolsters supporting the sides, a longitudinal beam or member extending from bolster to bolster and a cross beam or member having its ends secured to the sides midway between the bolsters and extending through the longitudinal beam at or near the neutral axis thereof, substantially as described.

2. In a car, the combination of the sides, of bolsters supporting the sides, of a longitudinal beam extending continuously from bolster to bolster and having a hole cut through the same at or near its neutral axis and midway between the bolsters, of a cross beam or member connected at its opposite ends to the car sides and extending through the hole in 95 the longitudinal beam and secured to said beam, substantially as described.

3. In a car, the combination of the sides, of a bolster supporting the sides, of a central longitudinal beam or member extending continuously from bolster to bolster, of a cross beam or member extending through said longitudinal beam or member at or near its neutral axis and secured to the car sides midway between the bolsters, and means for supporting 100 said central and cross beams or members at their intersection, substantially as described.

4. In a car, the combination of a central longitudinal beam, of a cross-beam intersecting 115 said longitudinal beam, a strut secured to said cross-beam at its intersection with the longitudinal beam, and a tie extending from said strut adjacent to the opposite ends of the cross-beam, substantially as described.

5. In a car, the combination of a longitudinal beam of inverted-V shape, of an I-beam cross member extending through said longitudinal beam, and a plate secured to the web of said cross-beam within the longitudinal beam and provided with flanges for securing 125 said cross-beam to said longitudinal beam, substantially as described.

6. In a car, the combination of a longitudinal beam of inverted-V shape, of a cross-beam extending through said longitudinal beam be- 130

low the ridge thereof, of a filler-block interposed between the top of said cross-beam and the ridge of the longitudinal beam, substantially as described.

5 7. In a car, the combination of the sides, of a longitudinal beam, of a cross-beam extending from side to side and through said longitudinal beam, of a tie, a strut extending between said tie and cross-beam, said tie extending to the outer extremities of said cross-beam, substantially as described.

10 8. In a car, the combination of the sides, of a hollow longitudinal beam, of a cross-beam extending through said longitudinal beam and secured to the car sides, of a strut depending from said cross-beam, said strut having arms or brackets engaging the lower surface of the longitudinal beam, and a tie-rod extending under said strut and having its ends extending through the car sides and there provided with tension-adjusting means, substantially as described.

15 9. In a car, the combination of the sides, bolsters connected to the sides, a longitudinal beam extending from bolster to bolster, a cross-beam having its ends secured to the sides and extending through the neutral axis of the longitudinal beam at the longitudinal center thereof, and means for securing together said 20 cross and longitudinal beams, substantially as described.

30 10. In a car, the combination of the sides, of a cross-beam extending from side to side, a strut depending from said cross-beam, a tie-

rod extending from said strut through the 35 sides of the car, the ends of said tie-rod being threaded, and nuts for the threaded ends of said tie-rod, substantially as described.

11. In a car the combination of the load-in- 40 closing sides, bolsters supporting the same, a longitudinal beam or member extending from bolster to bolster, a cross-beam having its ends abutting and secured to said sides, said cross-beam passing through the longitudinal beam and supporting it, and a tie-rod for the cross- 45 beam passing beneath the longitudinal beam.

12. In a car, in combination, the sides, a longitudinal beam, a cross-beam extending from side to side and passing through the longitudinal beam, a strut bearing against the 50 under side of the cross-beam where it crosses the longitudinal beam, and a tie-rod for said strut.

13. In a car, the combination with the sides, a longitudinal beam in the form of an inverted 55 V, a cross-beam secured to the sides and passing through openings in the longitudinal beam, means for securing the longitudinal beam to the cross-beam, a strut secured to the cross-beam beneath the longitudinal beam, and 60 a tie-rod passing beneath said strut.

In testimony whereof I hereunto affix my signature in the presence of two witnesses.

FRANK S. INGOLDSBY.
